CLAIM

The ornamental design for a capsule machine, as shown and described.

DESCRIPTION

FIG. 1 is an isometric view of a design of a capsule machine, according to a first embodiment of the invention.

FIG. 2 is a front view of the design shown in FIG. 1.

FIG. 3 is a right side view of the design shown in FIG. 1.

FIG. 4 is a rear view of the design shown in FIG. 1.

FIG. 5 is a left side view of the design shown in FIG. 1.

FIG. 6 is a top view of the design shown in FIG. 1.

FIG. 7 is a bottom view of the design shown in FIG. 1.

FIG. 8 is an isometric view of a design of a capsule machine, according to a second embodiment of the invention.

FIG. 9 is a front view of the design shown in FIG. 8.

FIG. 10 is a right side view of the design shown in FIG. 8.

FIG. 11 is a rear view of the design shown in FIG. 8.

FIG. 12 is a left side view of the design shown in FIG. 8.

FIG. 13 is a top view of the design shown in FIG. 8; and,

FIG. 14 is a bottom view of the design shown in FIG. 8.

The broken lines in the drawings represent portions of the capsule machine and form no part of the claimed design.

1 Claim, 14 Drawing Sheets
